UNITED STATES PATENT OFFICE.

CHRISTIAN PÖHLMANN, OF AUGSBURG, GERMANY, ASSIGNOR OF ONE-HALF TO MARBURG BROTHERS, INC., OF NEW YORK, N. Y., A CORPORATION OF NEW YORK.

MACHINE OR RAPID-FIRE GUN OR THE LIKE

Application filed March 27, 1924. Serial No. 702,322.

all whom it may concern:

Be it known that I, CHRISTIAN PÖHLMANN, a citizen of Germany, residing at Lurstrasse 35, Augsburg, Germany, have invented certain new and useful Improvements in Machine or Rapid-Fire Guns or the like, of which the following is a specification.

It is well known, that in machine- or rapid-fire- guns, and the like, prolonged rapid firing has heretofore only been possible with water-cooled guns. Water-cooling, however, has many serious disadvantages, such as necessitating carrying cooling water in the gun jacket, and in reserve reservoirs, requiring much time and great exertions for replenishing the necessary cooling water supply, sometimes from great distance and at great danger. Steam being produced in prolonged action furthermore imposes positions, increasing the danger of handling the gun. On the other hand, if the guns are idle for long periods during cold weather, the water may freeze, getting the gun out of order. For these and other known reasons, particularly where local conditions make it necessary, air-cooled guns are used to a considerable extent, firing being necessarily much slower if continued firing is required, or otherwise long periods for cooling off being necessary, after short series of rapidly fired shots. Nevertheless, in cases where it is very difficult or impossible to get cooling-water, and where guns must be used in dry or difficult territory, the air-cooled system is superior to the water-cooled system. In aeroplanes, where rapid firing occurs but only short series of shots are being fired, the air-cooled system is very efficient.

My invention constitutes a decided progress over both, water-cooled and air-cooled systems, inasmuch as it permits as rapid and even more prolonged firing as with water-cooled guns or rifles, without having many of the disadvantages connected with the latter, being independent of local conditions, always ready for instant use, always maintaining its maximum efficiency, requiring no moving and replenishing of water, being capable of more continuous use, handled and moved more easily and rapidly.

permitting concentration solely on firing and getting munition, etc.

In trying to find a solution of the problem, the inventor realized, that it is not only necessary to use a large quantity of cooling-air during each shot, but that with increasing rapidity of firing, at prolonged firing periods the amount of cooling-air, necessary for each shot, must be greatly increased, because the air, traveling past the rifle- or gun-barrel at a higher speed, absorbs less heat per unit of air, than if traveling at a lower speed. In other words, the volume of cooling-air must increase much faster than the number of shots being fired during a given period of time. Applicant's researches proved, that if a plurality of successively placed and properly designed gas or air ejector nozzles are used, and are properly arranged, adjoining to the outlet of the barrel, the suction and speed of the cooling-air currents, being produced by the exhaust powder gases, passing through the nozzles, increases considerably faster than the number of shots being fired within a given period of time. This having been proven, the limit of the rapidity at which shots can successively be fired for prolonged periods, depends mainly on the speed at which heat may be transmitted from the inner surface to the outer surface of the barrel. The necessity and difficulty of conducting the heat in this manner, has also been partly overcome by applicant, by creating a strong suction at the barrel outlet, at the moment the lock is opened, while the used cartridge is taken out, and during reloading, thus producing cooling-air currents within the barrel, cooling the latter internally and cleaning it of powder gases.

In order to make full use of this improved cooling device, applicant had to produce a new device, for greatly increasing recoil, which enables reloading the rifle or gun as fast as firing is permitted by the improved air-cooling.

The novel and original features of my air-cooling and of my improved recoil device, which, combined, are necessary, in order to get the greatest results, will be fully described and explained on hand of my drawings, which show a few designs.

which may be varied considerably, in view of the broad principles involved in my invention.

Referring now to the attached drawings, 5 Fig. 1 shows a longitudinal section through a part of my rifle or gun. Fig. 2 shows a longitudinal section of another design, containing my improved recoil mechanism. Figs. 3 and 4 show respectively on a somewhat larger scale, the front portion of the barrel and ejector nozzles in combination with my recoil mechanism in respective positions, immediately before and after a shot has been fired. Figs. 5 to 8 show respectively cross-sections of different designs of my recoil mechanism; Fig. 9 shows in cross-section a portion of the barrel with another design of the recoil mechanism. Fig. 10 again shows a different design as shown in Figures 3 and 4, the nozzles being made in separate sections and being screwed together. Figs. 11 to 14 are cross-sections of various designs, showing improved features in the design of conductors and of bearings or supports for barrel and conductor, and showing means for cooling the gun-chest and rear bearing for the barrel, etc.

Referring now more particularly to Fig. 1, 1 represents a rifle- or gun-barrel, 2, 3, 4 are respectively ejector nozzles, 5 is a conically shaped expansion nozzle, being shown herein as extension of nozzle 4. 7 represents an outer casing or cover. The ejector nozzles may all be connected together by webs, as shown herein. 6 are webs, which may support the nozzles within the outer cover 7. 1 is a rear portion of the barrel, which is thickened, 9 is a bearing for the rear end of the barrel, which bearing may be a part of the outer cover 7, as shown herein. 10 indicate inlets, permitting air to enter into a space within the cover 7. 11 represents cooling-webs, which latter may be one piece with the barrel. 12 is an air conductor or tube, for guiding cooling-air currents along the barrel, as will be explained later on, cooling-air being brought into close contact with the barrel and webs. 13 and 14, respectively, are showing additional air holes, permitting cooling-air currents to enter into the space being formed between conductor 12 and cover 7, for isolating and cooling the outer cover 7, the air afterwards leaving through holes 14. The outer cover may thus be easily handled, during prolonged actions or immediately thereafter. 15 and 16 respectively, represent the korn or fore sight and the notch, forming together the aiming device, which may conveniently be arranged on the outer cover 7. The object of the ejector nozzles 2, 3, 4, is, to create a strong suction of cooling-air, while the exhaust powder gases, are rushing through these nozzles, after a shot has been fired, as will all be explained more fully later on. A fur-

ther object of the expansion nozzle 5, is, to gradually expand the outrushing powder gases, in order to deaden the sound of the exhaust powder gases as much as possible.

Referring now to Figure 2, the same numbers apply to similar parts, as before, the design varying, however, in important points, as will be fully explained. 17 represents a thickened end portion of the barrel, being shown herein as one piece with the barrel, but which may be screwed onto the latter. 18 indicates a ring shaped space between part 17 and the outer cylindrical surface of the ejector nozzle 2. 19 indicates the face of part 17. 22 may be extensions of the webs, which connect the nozzle 2 and 3, being so arranged that the extensions form bearings or supports for part 1 and for the barrel. The webs 11 on the barrel are shown herein to run spirally and the pitch may increase towards the forward end of the barrel. The conductor 12 is of a larger diameter at its rear end, being taper and having gradually decreasing diameter in forward direction. The purpose being to increase the velocity of the air gradually from the air inlet end. The webs may or may not reach up to part 17. The expansion nozzle 5, shows several openings 33, whereby it may act in a double-capacity of ejector nozzle and expansion nozzle. Fig. 2 further shows my improved device for recoil, which will be fully explained on hand of Figs. 3 and 4.

Referring now to Figs. 3 and 4, Fig. 3 shows a portion of the forward end of the barrel and conductor and the ejector nozzles embodying my recoil device, the barrel and member 17 being in their position of rest. If a shot is being fired, the barrel and member 17 are thrown backwards into the position shown in Fig. 4, through momentary back pressure which is being created within nozzle or member 2, through the exhaust powder gases, as will later on be more fully explained. As soon as the back pressure is relieved, the barrel and member 17 are again quickly thrown in forward direction into the position of rest by means of a spring. By selecting the opening of the nozzle 2, greater or smaller, the back pressure of the exhaust powder gases may be decreased or increased, at will, thereby decreasing or increasing the recoil, as may be desired. A powerful means is thus being created, which enables to load or reload the gun as fast as desired, or as fast as the cooling device may permit. This will be later on more fully explained. The object of the ejector nozzles, 3, 4, and nozzle 5, as shown in Figs. 3, and 4, is to create a strong suction of cooling air, through the action of the exhaust powder gases, similarly as explained heretofore in connection with Fig. 1, while the gases are rushing through the nozzles,

after a shot has been fired. It will be seen from Fig. 3, that in its position of rest, the member 17 closes nozzle 2, preventing air from flowing through nozzle 2, the air momentarily flowing only through nozzles 3, 4 and 5, as indicated by thin lines and arrows. A moment after a shot has been fired, the barrel and member 17, as explained, are thrown towards the right, in position as shown in Fig. 4, whereupon the member or nozzle 2 is open to cooling air currents, the latter cooling the nozzle 2 now also from within and at the same time creating a strong suction at the barrel outlet, thereby sucking cooling air through the barrel, cooling the latter also from within and cleaning it of powder gases, because the lock is opened at that moment and the spent cartridge is automatically removed, before the gun is being automatically reloaded, which may all be accomplished within a small fraction of a second. The barrel and member 17 are quickly thrown back again, into their position of rest (Fig. 3) by means of a spring, which need not be shown. Immediately after the barrel has reached its position of rest, the next shot is being fired and the same series of motions or actions are repeated, and so on. The greater the rapidity of the shots, the more steady and permanent becomes the flow of the cooling air, on account of the great momentum of the stream of cooling air, which latter moves at an exceedingly high velocity, the air being sucked in through openings 10 (Figs. 1 and 2) and through conductor 12, passing out through the nozzles into the open air, as clearly indicated by thin lines and arrows, see Figs. 3 and 4, the heavy line and arrow representing the direction of flow of the exhaust powder gases. Thin dotted lines and arrows, represent leakage of gases at the moment exhaust powder gases are partly stowed or penned up within the nozzle 2 and before the barrel and member 17 have been thrown towards right. It will be seen, that the gases, leaking out between members 2 and 17, are directed forwardly, into nozzle 3, carrying with them additional air instead of disturbing the steady flow of cooling air. It will be noted, that the openings 33, being provided within the expansion nozzle 5, also have the purpose, after the exhaust powder gases have passed out, to permit cooling air to flow out at the forward end of the nozzle 5, thus preventing momentary back pressure, in the space surrounding the nozzle 5, which would otherwise disturb the steady flow of the cooling air in forward direction. As previously explained, air is also being sucked in through holes 13 in the outer cover 7, and through the annular space being provided between the conductor and the outer cover, heat-insulating the latter and keeping it cool during action, at the same time cool-

ing the conductor from without. Figs. 5 to 8 show different designs of the two members of my improved recoil mechanism co-operating in producing increased recoil; Figs. 7 and 8 are showing the end surface of the part 17, rilled or broken, as will later on be better explained.

Fig. 9 shows a different design of my recoil mechanism, wherein the ejector nozzles are arranged movably, instead of being stationary, as in previous designs, the principle of the recoil device remaining the same as before.

24 represents herein a dish or plate, being a part of the ejector nozzle 4; 32 is a spring, for returning the nozzles to their position of rest after each shot; 26 is a thickened part of the outer cover 7, having a sliding surface for the dish 24. 25 is an adjustable sleeve or nut, being screwed into the outer cover and having a sliding surface for the forward end of the nozzles; 29 is a slot in the sleeve; 28 is a block; 27 being a threaded end of said block, the latter being screwed into the expansion nozzle 5. The block 28 being arranged slidable within the sleeve 25, within the limit of the slot, the latter forming a stop for the block, both in the position of rest and limiting forward motion of the block and nozzles during a shot. Normally, the block is resting against the inward surface of the slot as shown, the sleeve 25 forming at the same time a firm rest or thrust bearing for one end of the spring 32, the other end of the spring resting against the movable dish 24, the latter being a part of the nozzles as explained before, moving with the same when a shot is being fired. 30 is a turnable pin, being carried by one end of said block. 31 is a rod or shaft, being suspended on and operated by the pin 30, the rod operating in turn a loading mechanism of the gun in known manner. It will be seen that air-cooling has also been shown around the expansion nozzle 5 and air openings are provided at or near the end of the nozzle in order to produce both cooling and a more steady stream of air, whereby also the spring is cooled.

Fig. 10 shows a design wherein the nozzles are stationary and wherein only the barrel and the member of the recoil mechanism, which is attached to the barrel, are movable. The nozzles are shown herein separately, demountably, or exchangeably, being adapted to be taken apart or assembled by means of threaded ends, which make it possible to carefully finish or polish each nozzle, in order to obtain the greatest efficiency, and which also permits to exchange nozzle 2, which latter, as explained heretofore, controls the speed at which the recoil mechanism may operate the reloading mechanism. It is advisable to make nozzle 2 of material which is very strong and can

withstand great heat, while nozzles 3, 4, and 5 may be of aluminum in order to make them light and good heat conductors.

Fig. 11 shows a design wherein the barrel 5 and the nozzles are stationary and wherein the conductor 12 and the gas ejector nozzles are made in one piece, being screwed into the outer cover 7 at its forward end and being preferably supported near its middle 10 portion, in the outer cover. 41 is a cooling sleeve, surrounding the barrel, 11 being cooling webs on the sleeve, the sleeve and webs, forming one part with the conductor, some of the webs being extended, serving as 15 means for connecting the nozzles and the conductor, as shown herein. By unscrewing the nozzles at their forward end, the nozzles and conductor may easily be taken out of the outer cover; 42 shows a rifle- or 20 gun-chest, the outer cover 7 being fastened to the chest in any known manner, so that it may easily be demountable, together with the conductor and air nozzle, making it possible to quickly replace the barrel, if it 25 should become necessary to do so. 43 and 44 represent openings, the latter being adapted for permitting cooling air to be sucked in, in sufficient quantity to cool the rifle- or gun-chest and the bearings of the 30 barrel, the air being drawn into the cooling space arranged between the cover 7 and the conductor, additional cooling air entering through openings 10. By regulating the size of openings 10, 43 and 44 the air currents 35 may be regulated. It will be noted, that the conductor has been greatly shortened and has been arranged close to the nozzles, directing the cooling air closer towards the nozzles. In order to prevent 40 swelling of the barrel causing trouble, in taking the gun apart, the cylindrical hole within the sleeve may be slightly larger in diameter than the barrel, the latter being supported within the sleeve and centered 45 therein by a short taper hole, as shown.

Fig. 12 shows a design, wherein the barrel and nozzles again are stationary and wherein the rear end of the conductor is formed in such manner, that the cooling air, which is sucked into openings 10 at very high speed, is directed forwardly with as little whirling, and as little loss of speed is possible, the outer part of the conductor, as shown, having a long cylindrical shape, a ring shaped space being arranged between the outer surface of the conductor and the outer cover 7, air holes 13 being provided within the outer cover 7, similarly as in Figs. 1 to 4, for cooling air to be sucked in, and principally, for keeping the outer cover cool, similarly as in previous designs. It will be noted, that the nozzles are herein forming a separate part, the latter being screwed into the forward end of the outer cover; in such manner, that the conductor

is being held firmly between the nozzles and the rifle- or gun-chest, the webs connecting the nozzles being preferably arranged with in a plane with the webs of the conductor, after being assembled.

Fig. 13 represents a design wherein my improved recoil device is employed in different manner as explained before, the conductor 12 being one piece with the members 17 of the recoil device and being firmly arranged on the barrel and moving together with the latter during or immediately after each shot. It will be noted that the conductor has taper holes in portions towards the rear and front ends, the conductor being 70 fitted to the barrel at these taper holes, a cylindrically shaped portion of the hole within the conductor being slightly larger in diameter than the respective barrel diameter, though the difference in the respective 75 diameters is very slight and need not be shown herein. 42 again shows the rifle- or gun-chest and 43 and 44 show respectively air inlet and outlet holes, for air-cooling 80 purposes, similarly as shown in Fig. 11. 22 shows continuations of webs 6, serving as supports for the member 17 of the recoil device and of the conductor. The outer cover 7 and the nozzles, which latter may again be screwed into the cover, may be 85 taken off together if desired, whereupon the conductor may be taken off and the barrel replaced, if required. Fig. 14 differs from 90 Fig. 13, mainly, in the manner in which the member 17 and conductor 12 are supported at their forward end, within the outer cover 7, being guided by, and sliding within a 95 large round bearing, the latter being provided within the outer cover.

From the different drawings it will be 105 seen, that the barrel and conductor, as well as the nozzles have many cooling webs, offering a large cooling surface, the webs being not in direct contact with the outer cover, but adapted to absorb the heat from 110 the barrel and conductor and nozzles, the heat being in turn absorbed by the cooling air currents, the latter being produced by the exhaust powder gases. There are as few contact surfaces provided between the 115 conductor and nozzles respectively, and the outer cover, as possible, the object being to keep the outer cover cool, so that it may be easily handled at any time, and loaded on horses or carried by men, if necessary, and also to prevent heat or hot air currents from the outer cover to cause scintillating or flickering which latter would make accurate aim 120 impossible. For these reasons, heat insulating material may be inserted, wherever contact is unavoidable between the inner hot parts and the outer cover.

Suction openings, similar to openings 33, shown, have been used before in expansion nozzles, on rapid-fire-guns or the like, for in- 125 130

stance in British Patent No. 12,927 of 1910, but such expansion nozzles and the openings mentioned have not been used in connection with one or more compression and expansion nozzles, that is, in combination with a nozzle or nozzles, wherein exhaust-powder-gases are expanded, while cooling-air is simultaneously being compressed within the same nozzle, as is the case within gas ejector nozzles 3 and 4. According to the British patent, such slots within the expansion nozzle, should do all of the required suction of cooling air, which it is not capable of doing. These slots assist somewhat in producing suction of cooling-air and in producing a more steady flow of cooling-air, as explained hereinbefore. They also assist in keeping the outer cover cool, but they cannot alone provide a successful air-cooling system for rapid-fire-guns or the like.

I will now more fully describe the action of my device or combination of devices. After each shot, following the projectile, exhaust-powder-gases are rushing with tremendous velocity, through ejector nozzles 2, 3, 4, and nozzle 5, and as a result of friction between the gases and the air, the latter being contained in the surrounding conically shaped spaces, a large quantity of this air is borne along with the gases, through the nozzles, the mixture of gases and air being discharged into the open atmosphere. A strong vacuum is being created within the spaces surrounding these nozzles, which in turn causes a strong suction of air through openings 10 (Figs. 1 and 2) and through the conductor, as well as through the additional openings 13 and 14. Cooling-air may also be drawn in through openings 42 and 43 within the gun-chest, (Figs. 11, 13 and 14) as previously explained. From Figs. 3 and 4 which show more clearly the action of my devices, it will be seen, that nozzle 2 is closed at first when a shot is being fired, air therefore is being carried or borne in through nozzle 3, through friction being created between the gases and the air, the air being condensed or compressed within nozzle 3 and forming an outer cone-shaped cover, surrounding the main body of gas. It will be understood, that the energy, being used up, for moving and for condensing or compressing the air, is being furnished by expansion of the high pressure exhaust-powder-gases, which latter rush out mainly through the center portion of the cone and which continue, at the center, to exert a strong propulsive pressure on the projectile, after the latter has emerged from the barrel, as is well known. At the same time, the gases expand sidewise or in radial direction, advancing in the shape of a cone, gradually increasing in diameter. The object of condensing or compressing air, or a mixture of the latter with a portion of the gases, within

nozzle 3, is to form again a compact outer surface of the stream of gas and air, rushing from the latter nozzle, capable of carrying along air from the outer air cone, surrounding nozzle 4, condensing and compressing again the air last drawn in, and so on. As the surrounding air-cone is getting larger in diameter, the friction surface between the gas or mixture and between the air, increases more and more, and as the speed of the gases decreases, the time being provided for the acceleration of the surrounding air increases. While the amount of air, being borne or drawn into the nozzles, is not exactly proportional to the frictional surface, the volume of air, being sucked or drawn into the nozzles, is a function of the frictional surface. The volume of cooling air being sucked through the conductor, is therefore greatly increased, by using a plurality of nozzles, the latter successively increasing in size or capacity as shown. It will also be understood, that unless a certain degree of compactness is maintained in the outer conical surface of the exhaust-powder-gases or mixture, violet whirling action is created within the nozzles, whereby the flow of the incoming cooling-air, is decreased or prevented. Again, if a plurality of ejector nozzles are used successively, a greater amount of kinetic energy is being developed, as a result of greater possible total expansion in successive steps, this kinetic energy being consumed in accelerating the speed and compressing the large volume of cooling-air. The total loss in useful energy is very small, because a part of the energy would ordinarily be wasted by radial expansion, if the gases rush directly into the open air. For all these reasons, a plurality of successive nozzles produce a far more efficient cooling of the barrel, but a plurality of nozzles of a character as shown herein has not been used heretofore for producing cooling air currents for cooling rapid fire-guns or the like.

The advantages in using a plurality of successive nozzles, each successive nozzle having a greater capacity or larger internal diameter than the preceding nozzle, as shown in my drawings, will now be further explained. In ordinary guns, wherein gases enter directly into the open atmosphere, the gases normally expand, forming a cone, increasing in diameter, its walls forming a small angle to the axis. The successive nozzles should be of relatively increasing capacity or size, so that the powder gases may expand radially, gradually, but that air may be carried or drawn into each nozzle, and compressed in such manner, that the stream, consisting near its center of exhaust powder gases, and near its outer surface more or less of a mixture of gases and air, is maintained substantially compact and unbroken.

If this stream is partly breaking up, violent whirling is produced in the surrounding air spaces, whereby axial cooling air currents are greatly reduced or weakened.

- 5 One of the main objects of the invention is to produce as strong axial cooling currents as possible, and for this reason it is important, that the successive nozzles are of such relatively increasing capacity, that 70
10 unnecessary back pressure as well as whirling are avoided.

Another feature in applicant's device which is of advantage and novel, is, that all 75 nozzles are cooled both from without and 15 within by the cooling air currents. This is important because the powder gases would otherwise quickly burn the nozzles.

It should be explained, that the expansion nozzle 5, has primarily the object, of permitting further expansion of the outrushing 80 mixture of gas and air, for the purpose of reducing the noise of the exhaust as much as possible. In view of the large volume of air being mixed with the gases, smoke is 85 25 also much decreased. The holes 33 in the expansion nozzle, increase the suction of air still more and permit the rapid flow of cooling air to become more steady, reducing momentary back-pressure and whirling, 90 30 which would otherwise be created between shots and which would reduce the flow of cooling-air, which in turn would reduce the efficiency of the rifle or gun.

Some further explanation is required regarding the action of my improved recoil 95 device. The instant, the shot has left the barrel, the exhaust powder-gases rush through the nozzle 2. Since, however, the outlet of nozzle 2 is made somewhat small, 100 40 the gases which rush out, expanding slightly radially, are stowed or penned up, to some extent, within the nozzle 2, causing momentarily a strong back-pressure. It will be seen, that the member 17, at this moment, keeps the rear portion or end of this nozzle closed, the gases therefore are exerting momentarily a powerful pressure on the member 17, whereby the latter and the barrel, are very quickly thrown backwards, 105 45 from their position of rest, (Fig. 3) until they reach the position shown in Fig. 4. It will be understood, that, while the barrel moves and before it reaches the position shown in Fig. 4, the main body of the gases 110 50 has already reached the open air and the back-pressure is entirely relieved. As the opening between the members 17 and 2 increases, the latter member or nozzle 2 begins to act as an ejector nozzle. When the member or nozzle is fully opened, the exhaust has entirely passed out, and as a result of the large momentum of the stream of cooling air within the conductor etc., the cooling-air passes easily around the rounded 115 55 outer portion of the member 17 and through

nozzle 2, cooling it now from within and creating a strong suction at the barrel outlet, at the moment when the spent cartridge is being automatically thrown out and the barrel is being reloaded, thus sucking a stream 70 of cooling air through the hole within the barrel, scavenging and cooling the latter from within. This method of cooling has the decided advantage, that it reaches the surface or portion of the barrel which requires most to be cooled and that it cleans the barrel of powder-gases, which also greatly increases the life of the barrel. The barrel and member 17 are quickly returned to their position of rest, by means of a spring 75 or any other known means. When the member 17 and the barrel reach their position of rest (Fig. 3) the gun has been reloaded and the same motions of the said parts successively take place, and so on. 80

As mentioned before, the thin lines and arrows represent the flow of the air, the thick line and arrow represents the flow of the powder gases and the dotted lines and arrow represent leakage of exhaust powder gases through the annular space 18, being provided between the members 17 and 2. It is advisable to guide the member 17 accurately, concentrically to the member or nozzle 2, thus permitting the annular space 18 to 90 be made small. The face 19 may be broken or rilled as shown in Figs. 7 and 8, in order to reduce whirling within the nozzle 2 and in order to produce a maximum of recoil. 95 The leakage may be somewhat reduced by such rills or by a broken or rough surface 19. My recoil device can be made to act as fast as desired, as stated heretofore, by changing the opening of the nozzle 2. My recoil device consumes only a very small 100 amount of the useful energy of the exhaust powder-gases, at any rate not more than is at present being consumed with existing recoil devices. 105

My recoil device is an almost necessary part in my system of air-cooled gun, or more correctly, my air-cooling system is a necessary adjunct if my improved recoil device is used for air-cooled guns. The device preferably consists of two members, the one of the members being attached to the barrel and the other one of the members having the shape of a nozzle as shown. Either the member attached to the barrel may be movable, the other member or nozzle being stationary, or the member or nozzle 2, as shown in Fig. 9, may be movable, while the member 17 may be either stationary or may also be movable, the movable member or members, either separately or jointly operating 110 the lock, reloading the gun. 115 120

In shortly resuming the advantages of my air-cooled machine- or rapid-fire-gun, as compared with water-cooled guns, it may fire as rapidly as the latter, when the water- 125 130

cooled guns operate under favorable conditions. My gun may be fired as rapidly for as long series of shots as water-cooled guns, requiring no carrying of cooling medium, and no stops for replenishing the cooling medium, and no attention whatsoever to the cooling medium, the cooling system being very simple, nothing to get out of order; all time may be concentrated on getting munition and operating the gun. It has always maximum efficiency, is always ready. There is no steam betraying position, less smoke, and less noise. It is lighter and more easily handled and transported than water-cooled guns. The barrel is well scavenged and internally cooled; very accurate aiming is possible.

As compared with existing air-cooled rifles, my gun may fire several times as rapid if prolonged periods of firing are required.

Having thus explained my invention, and the advantages thereof, I claim:

1. In a machine gun or the like, a barrel, a plurality of gas ejector nozzles, being arranged successively and adjointingly to the outlet of said barrel, each successive one of said nozzles having a larger capacity or internal diameter than the preceding one of said nozzles, said nozzles being adapted to produce strong cooling air currents while exhaust powder gases are passing through the same, means, employing said currents for cooling said barrel.

2. In a machine gun or the like, a barrel, a plurality of gas ejector nozzles, being arranged successively and adjointingly to the outlet of said barrel, each successive one of said nozzles having a larger capacity or internal diameter than the preceding one of said nozzles, said nozzles being adapted to produce strong cooling air currents while exhaust powder gases are passing through the same, means, employing said currents for cooling said barrel and for cooling said nozzles internally and externally.

3. In a machine gun or the like, a barrel, a plurality of gas ejector nozzles, being arranged successively and adjointingly to the outlet of said barrel, each successive one of said nozzles having a larger capacity or internal diameter than the preceding one of said nozzles, said nozzles being adapted to produce strong cooling air currents while exhaust powder gases are passing through the same, an air conductor surrounding said barrel, cooling air space being provided between said barrel and conductor, said space communicating at one end of said conductor with cool air of the atmosphere and at its other end with said nozzles.

4. In a machine gun or the like, a barrel, a plurality of gas ejector nozzles, being arranged successively and adjointingly to the outlet of said barrel, said nozzles being adapted to produce strong cooling air cur-

rents, while exhaust powder gases are passing through the same, an air conductor surrounding said barrel and nozzles, cooling air space being provided between said barrel and nozzles and conductor respectively, 70 said space communicating at one end of said conductor with cool air of the atmosphere and at its other end with said nozzles, said currents cooling said barrel and cooling said nozzles from within and without. 75

5. In a machine gun or the like, a barrel, a plurality of gas ejector nozzles, being arranged successively and adjointingly to the outlet of said barrel, each successive one of said nozzles having a larger capacity or 80 internal diameter than the preceding one of said nozzles, said nozzles being adapted to produce strong cooling air currents while exhaust powder gases are passing through the same, an air conductor surrounding said 85 barrel, cooling air space being provided between said barrel and conductor, cooling webs being arranged between said barrel and conductor, adapted to absorb heat from said barrel. 90

6. In a machine gun or the like, a barrel, a plurality of gas ejector nozzles, being arranged successively and adjointingly to the outlet of said barrel, each successive one of said nozzles having a larger capacity or internal diameter than the preceding one of said nozzles, said nozzles being adapted to produce strong cooling air currents while exhaust powder gases are passing through the same, an air conductor surrounding said 100 barrel, cooling air space being provided between said barrel and conductor, an outer cover surrounding said conductor, providing cooling air space between said cover and conductor, said respective spaces communicating at one end of said conductor and cover, respectively, with cool air of the atmosphere and at the other respective ends with said nozzles. 105

7. In a machine gun or the like, a barrel, one or more gas ejector nozzles being arranged successively and adjointingly to the outlet of said barrel, an air expansion nozzle being placed adjacently to one of the said ejector nozzles, slots or openings being 110 provided in said expansion nozzle, said nozzles being adapted to produce strong cooling air currents while exhaust powder gases are passing through the same, means, employing said currents for cooling said barrel. 115

8. In a machine gun or the like, a barrel, a plurality of gas ejector nozzles, being arranged successively and adjointingly to the outlet of said barrel, each successive one of said nozzles having a larger capacity or 120 internal diameter than the preceding one of said nozzles, said nozzles being adapted to produce strong cooling air currents while exhaust powder gases are passing through the same, an air conductor surrounding said 125

130

barrel, cooling air space being provided between said barrel and conductor.

9. In a machine gun or the like, a barrel, two members, the one of the said members being placed movably, adjacently to the outlet of said barrel, the other one of the said members being arranged, adjoiningly to said movable member, the said members cooperating, momentarily creating backpressure of the exhaust powder gases when a shot is being fired, and whereby the said movable member receives a quick movement, increasing recoil, means returning said movable member to its position of rest before the next shot is being fired, the one of the said members acting successively and intermittently, first increasing recoil and secondly as gas ejector nozzle, in the latter case producing suction and cooling air currents through the action of the exhaust powder gases passing through said nozzle, one or more gas ejector nozzles being arranged adjoiningly to said members, said latter nozzle or nozzles having a larger internal diameter or diameters than said member and said nozzle or nozzles being adapted to increase suction and cooling air currents, means, employing said currents for cooling said barrel.

10. In a machine gun or the like, a barrel, two members, the one of the said members being placed movably, adjacently to the outlet of said barrel, the other one of the said members being arranged, adjoiningly to said movable member, the said members cooperating, momentarily creating backpressure of the exhaust powder gases when a shot is being fired, and whereby the said movable member receives a quick movement, increasing recoil, means returning said movable member to its position of rest before the next shot is being fired, the one of the said members acting successively and intermittently, first increasing recoil and secondly as gas ejector nozzle, in the latter case producing suction and cooling air currents through the action of the exhaust powder gases passing through said nozzle, one or more gas ejector nozzles being arranged adjoiningly to said members, a gas expansion nozzle being arranged adjoiningly to said nozzles, each successive nozzle having a larger internal diameter than its preceding nozzle, said nozzles being adapted to increase suction and cooling air currents, means, employing said currents for cooling said barrel.

11. In a machine gun or the like, a barrel, a member being placed movably, adjacently to the outlet of said barrel, means, momentarily creating backpressure of the exhaust powder gases while a shot is being fired and whereby said member receives a quick movement, means, returning said member to its position of rest before the next shot is being fired, one or more air ejector nozzles being arranged adjoiningly to the outlet of said

barrel, and being adapted to produce strong suction and cooling air currents through the action of the exhaust powder gases passing through said nozzle or nozzles, means, employing said currents for cooling said barrel.

12. In a machine gun or the like, a barrel, a member being placed movably, adjacently to the outlet of said barrel, means, momentarily creating backpressure of the exhaust powder gases while a shot is being fired and whereby said member receives a quick movement, means, returning said member to its position of rest before the next shot is being fired, said member acting alternately and intermittently, first, increasing recoil, and secondly, as gas ejector nozzle, means, comprising one or more gas ejector nozzles in addition to said member, whereby strong suction and cooling air currents are being created within said space, through the action of the exhaust powder gases passing through said nozzle or nozzles.

13. In a machine gun or the like, a barrel, two members, the one of the said members being placed movably, adjacently to the outlet of said barrel, the other one of the said members being arranged, adjoiningly to said movable member, the said members cooperating, momentarily creating back-pressure of the exhaust powder gases when a shot is being fired, and whereby the said movable member receives a quick movement, increasing recoil, means returning said movable member to its position of rest before the next shot is being fired, the one of the said members acting successively and intermittently, first increasing recoil and secondly as gas ejector nozzle, in the latter case producing suction and cooling air currents through the action of the exhaust powder gases passing through said nozzle, means, employing said currents for cooling said barrel.

14. In a machine gun or the like, a barrel, two members, the one of the said members being placed movably, adjacently to the outlet of said barrel, the other one of the said members being arranged, adjoiningly to said movable member, the said members cooperating, momentarily creating backpressure of the exhaust powder gases when a shot is being fired, and whereby the said movable member receives a quick movement, increasing recoil, means returning said movable member to its position of rest before the next shot is being fired, the one of the said members acting successively and intermittently, first increasing recoil and secondly as gas ejector nozzle, in the latter case producing suction and cooling air currents through the action of the exhaust powder gases passing through said nozzle, one or more gas ejector nozzles being arranged adjoiningly to said members thereby increasing the suction and cooling air currents,

means, employing said currents for cooling said barrel.

15. In a machine gun or the like, a barrel, a member being placed movable, adjacently, to the outlet of said barrel, means, momentarily creating backpressure of the exhaust powder gases while a shot is being fired, and whereby said member receives a quick movement, increasing recoil, means, returning said member to its position of rest before the next shot is being fired, one or more air ejector nozzles being arranged adjoiningly to said outlet, in such manner, that strong suction and cooling air currents are being created through the action of the exhaust powder gases passing through said nozzle or nozzles, means, employing said currents for cooling said barrel, and means, momentarily creating suction at said barrel outlet for the purpose of cooling and cleaning said barrel internally.

16. In a machine gun or the like, a barrel, an air conductor surrounding said barrel and an outer cover surrounding said conductor, providing cooling air spaces between the said barrel and conductor and outer cover respectively, one or more gas ejector nozzles being mounted adjoiningly to the outlet of said barrel, said conductor and outer cover being at one of their respective ends in direct communication with the cool air of the atmosphere and communicating at their other respective ends with each other and with said nozzle or nozzles, the exhaust powder gases passing through said nozzle or nozzles, creating strong suction and cooling air currents within the said spaces.

17. In a machine gun or the like, a barrel, a member, being mounted movably and adjoiningly to the outlet of said barrel, means, momentarily creating backpressure of the exhaust powder gases while a shot is being fired, and whereby said member receives a quick movement, increasing recoil, means, returning said member to its position of rest before the next shot is being fired, an air conductor surrounding said barrel, an

outer cover surrounding said conductor, providing cooling air space between said conductor and said outer cover, means, comprising one or more gas ejector nozzles, whereby strong suction and cooling air currents are being created within said space through the action of the exhaust powder gases passing through said nozzle or nozzles.

18. In a machine gun or the like, a barrel, cooling webs on said barrel, an air conductor surrounding said barrel and said webs, an outer cover surrounding said conductor, providing cooling air spaces between said barrel and conductor and outer cover, respectively, one or more gas ejector nozzles, being mounted adjoiningly to the outlet of said barrel, the exhaust powder gases passing through said nozzle or nozzles, producing strong suction and air currents within the said spaces, for the purpose of cooling said barrel, conductor and cover.

19. In a machine gun or the like, a barrel, a plurality of air ejector nozzles being arranged adjoiningly to the outlet of said barrel, an air expansion nozzle being placed adjacently to said ejector nozzle, slots or openings being provided in said expansion nozzle, said ejector nozzles and expansion nozzle being adapted to produce strong suction and cooling-air currents through the action of the exhaust powder gases passing through said nozzles, means, employing said air currents for cooling said barrel.

20. In a machine gun or the like, a barrel, an air ejector nozzle being arranged adjoiningly to the outlet of said barrel, an air expansion nozzle being placed adjacently to said ejector nozzles, slots or openings being provided in said expansion nozzle, said ejector nozzle and expansion nozzle being adapted to produce strong suction and cooling air currents through the action of the exhaust powder gases passing through said nozzles, means employing said air currents for cooling said barrel.

CH. PÖHLMANN.
